GLADEON M. BARNES, OF HASTINGS, MICHIGAN.

METHOD OF AND MEANS FOR TRANSPORTING HEAVY ARTILLERY.

Application filed August 4, 1924. Serial No. 730,117.

(GRANTED UNDER THE PROVISIONS OF THE ACT OF MARCH 3, 1883, 22 STAT. L., 625.)

The invention described herein, may be manufactured and used by or for the Government for governmental purposes without the payment to me of any royalty thereon.

5 The subject of this invention is a method of and means for transportation of heavy artillery and of emplacing same quickly in condition for firing. The invention includes a special type of gun carriage thus forming 10 a new system of artillery for use with a field army or for coast defense.

The exigencies of modern warfare have brought about the development of high powered heavy artillery and rendered it desired 15 able that such artillery be mobile.

Railway systems, which now cover most civilized countries with a net work of transportation lines, such lines usually extending to all important sea ports, provide a ready 20 and efficient means for the transportation of such artillery, permitting heavy artillery to be assembled, during war, at any threatened point and readily moved from such point to others, when desired.

25 Railway mounts of various designs have, consequently, been suggested and a number of such suggested designs actually produced; but all such mounts are necessarily cumbersome, and since the carriage and gun are 30 transported as a unit are extremely heavy and their transportation is limited by bridges and light roadbeds.

This invention contemplates the use of lighter, more easily fabricated and cheaper 35 structures and, to this end, the gun is transported on separate trucks, thereby relieving the gun carriage of shocks and strains incident to road travel with a heavy gun mounted thereon. The trucks are of a design 40 sign to be readily placed beneath the gun to receive its weight, or removed therefrom; and the special gun carriage, which is transportable as a separate unit, is designed to be run beneath the gun when the gun transporting trucks are removed so that the gun 45 may be supported in the cradle, the transporting means for the carriage being preferably removable therefrom.

This system of transportation includes em- 50 placements either previously prepared along the right of way, or constructed at the time of emplacement of the gun, as may prove most desirable.

That those skilled in the art may have a 55 thorough comprehension of the invention,

reference is had to the following description in conjunction with the accompanying drawings, which illustrate a preferred embodiment of the invention, and in which:

Fig. 1 is a view in side elevation of a 60 gun on its transporting trucks in position above an emplacement, jacks being shown in place to lift the gun from the trucks;

Fig. 2 is a similar view showing the gun transporting trucks removed and the gun 65 carriage run part way beneath the gun;

Fig. 3 is a similar view showing the carriage in gun supporting position ready to be lowered into emplaced position;

Fig. 4 is a plan view of the gun carriage, 70 partly in section on line 4-4 of Fig. 5 and with parts removed.

Fig. 5 is side elevation of the same;

Fig. 6 is a detail longitudinal sectional view taken through one of the gun carriage 75 jacks on line 6-6 of Fig. 8.

Fig. 7 is a vertical transverse section;

Fig. 8 is a section on the line 8-8 of Fig. 5;

Fig. 9 is a plan view of the forward truck 80 of the transport car.

In carrying out my invention a suitable transport car 10 (Fig. 1) is provided for the reception of the gun 11, the gun being removed from its mount for the purpose 85 of transportation.

The transport car 10 may be of any convenient form, the preferred form herein shown, by way of illustration, consisting of rear trucks 12 and 18 and a forward truck 90 13, which may be connected by the gun 11 when placed thereon, or, as herein shown, by side bars 14 which are secured to the side plates 15, pivotally mounted on the rear trucks. The plates 15 are formed at 95 their rear ends with spaced eyes 16 adapted to register with complementary eyes formed in the forward edges of the side plates 17 of a detachable rear truck section 18 so that the section may be connected to the car by 100 passing bolts through the registering eyes. The plates 15 and 17 are formed to provide a pivotal support for the breech end of the gun during transportation. The forward truck consists of the usual truck platform 105 on which is mounted a block 19, apertured to receive the side bars 14, which bars are provided with openings, not shown, alining with openings 20 in the block, so that pins, bolts or the like may detachably fasten the 110

front truck to the car. A suitable rest 21 for the gun is provided on top of the block in which the gun may be secured as by means of straps 22 which are hinged at 5 one end to the rest and bound to the gun by bolts passing through apertures in their free ends and secured to the rest in the usual and well known manner.

A locomotive is used to draw the car, and 10 special carriage described later, along the rails to the point of emplacement. This emplacement may be of suitable concrete, timber, or steel construction for the proper 15 emplacement of a gun. The form herein shown being of the circular pit type, for 360° traverse, but may be constructed to give any lesser field of fire. The removable rails across the pit are supported by suitable removable I beams 23. The car 10 is 20 brought to position over this emplacement, as seen most clearly in Fig. 1, and means employed, such as the rear jack 25 and front jack 26, for elevating the gun from the car. The rear truck 18 is then removed by 25 withdrawing the bolts 16'. The pins 20' are withdrawn and side plates 14 removed. The rear truck 12 is moved forwardly a sufficient distance to permit placing the jack 27, (Fig. 2), when the front jack 26 may be 30 removed and the trucks run forward from beneath the gun, to some convenient point. The gun is now supported by jacks 25 and 27, the center of gravity being at the point T between these jacks.

35 The gun carriage 28 (Fig. 2) is of special form provided with trucks 33 for ready transportation. It is also provided with jacks 29 housed in its side plates and operated in any approved way, as for example, 40 by worms 30 and worm wheels 31 as seen most clearly in Figs. 6, 7, and 8. The jacks carry at their lowermost extremities flanged wheels 32, adapted to contact the rails and support the carriage thereon when the jacks 45 are lowered. During transport the jacks are retracted or drawn up, the carriage being then supported by detachable trucks 33, only one of which is shown, connected to the front and rear ends of the carriage. To 50 provide a convenient method of attaching the trucks to the carriage, the carriage is formed at the front and rear ends of its side plates with spaced eyes 35 adapted to register with eyes 36 formed on the front 55 and rear trucks so that the trucks may be detachably connected to the carriage by passing bolts or the like through the eyes. The carriage herein illustrated being equipped with the usual elevating mechanism, training mechanism, range dial, sights, 60 electric lights, rammer and facilities for loading, azimuth circle and pointer and facilities for laying the gun in direction or elevation is supplied with a pedestal 37 containing a roller or ball bearing, adapted to

rest on the central reinforced pier of the emplacement, while, at the opposite end of the carriage, a pair of wheels 38 are mounted and are adapted to rest on a circular rail 39 in sections provided at the emplacement, thus supporting the carriage in its 70 pivotal movement during traverse.

When the carriage is brought to the point of emplacement, the jacks are forced down until the weight of the carriage is supported on the wheels 32, when the front and rear trucks are disconnected and removed. The gun being in position above the emplacement, as heretofore described, the carriage is run beneath the gun, the gun entering the opening in the cradle 40 as seen in Fig. 2. In this position the front jack 26 is replaced and the center jack 27 is removed. The carriage is then run as far back as the rear jack 25 will permit, at which point the rear jack may be moved to a position forward of the rear transom, Fig. 3, the gun during such movement being supported in the cradle. The jack is again brought into contact with the gun and the carriage is run back until it is finally in position (Fig. 3).

When the carriage is in position, the jacks are lowered and the carriage lowered at the same time through manipulation of its jacks 29 until the pedestal rests on the central pier of the emplacement to which it is then securely bolted and the wheels 38 on the circular rails 39. The jacks 25 and 26 are now removed and the jacks 29 on the carriage 100 are raised. The gun is fastened to the recoil and counter recoil rods of the cradle and after the removal of the rails and beams 23, can be fired.

It is to be understood that the trucks, 105 when removed during emplacement of a gun, may be taken care of either by bodily lifting them from the tracks or by running them out on short sidings provided for this purpose.

In some cases it may be desirable to transport the cradle, containing the recoil mechanism, with the gun, as one unit and the remainder of the carriage as the other unit to obtain better division of the weight or 110 to facilitate mounting at the emplacement.

The electrical power unit for this mobile system of artillery may be transported in a separate car using power leads to connect the generator in the car with the various 115 motors on the gun carriage such as the elevating motor, rammer motor, traversing motor, lighting system, and air compressor motor. When emplaced where electric power is available the mobile power plant will 120 not be required.

While the equipment herein illustrated and described is for use on railways, it is to be understood that the broad invention 125 is not limited to railway use as the same 130

principle may readily be applied to tractor drawn or self propelled artillery, as well as other mobile artillery.

I claim:

- 5 1. A gun mount, mobile supporting means removably attached to the mount for transporting the mount, and retractable temporary mobile supports carried by the mount for emplacing the mount.
- 10 2. A gun mount, mobile supporting means removably attached to the mount for transporting the mount, and temporary mobile supports carried by the mount for emplacing the mount.
- 15 3. A gun mount, mobile supporting means for the mount for transporting the mount and temporary mobile supporting means carried by the mount for emplacing the mount.
- 20 4. A system of mobile artillery embodying emplacements, a gun and its mount transportable as separate units, mobile supporting means for the gun, mobile supporting means for the mount, means for supporting one of said units in position above
- 25 the emplacement while removing its mobile supporting means and assembling the units, means for supporting the other of said units while removing its mobile supporting means and assembling it with the first of said units, 30 and means for connecting the mount to the emplacement.
- 35 5. A system of mobile artillery embodying an emplacement, a gun and its mount transportable as separate units, mobile supporting means for the gun, mobile supporting means for the mount, means for supporting the gun in position above the emplacement while removing its mobile supporting means and assembling the units, means carried by the mount for supporting the mount 40 while removing its mobile supporting means

and assembling it with the gun, said means operable to lower the mount upon the emplacement, and means for connecting the mount to the emplacement.

45

6. A system of mobile artillery embodying an emplacement, a gun and its mount transportable as separate units, mobile supporting means for the gun, mobile supporting means for the mount, means for supporting one of said units in position above the emplacement while removing its mobile supporting means 50 and assembling the units, the means supporting the units including means for lowering the assembled units to position upon the emplacement.

55

7. A system of mobile artillery embodying an emplacement, a gun and its mount transportable as separate units and having removable transporting means, means for supporting the gun in position, and means carried by the mount whereby it may be moved 60 into position to receive the gun and manoeuvred to its emplacement.

65

8. A system of mobile artillery embodying an emplacement consisting of a central pier within a circular pit, removable bridge rails 70 extending from the pier to the opposite side of the pit, a wheeled gun mount movable over said rails, and means carried by the mount for lowering it upon the central pier.

70

9. A system of mobile artillery embodying 75 an emplacement consisting of a central pier within a circular pit, removable bridge rails extending from the pier to the opposite side of the pit, a wheeled gun mount movable over said rails, and means for lowering the 80 mount upon the central pier.
